UNITED STATES PATENT OFFICE.

EDWARD ALBERT KLIWER, OF TULSA, OKLAHOMA, ASSIGNOR OF TWENTY-FOUR PER CENT TO F. G. LIPPITT, ONE THIRTY-SECOND TO J. W. CASTLEMAN, AND ONE-SIXTEENTH TO WALTER DAVID, ALL OF BRECKENRIDGE, TEXAS.

FIRE EXTINGUISHER FOR OIL WELLS.

Application filed April 12, 1923. Serial No. 631,643.

This application relates to improvements in fire extinguishing attachments for oil wells.

It is the object of the invention to provide an extremely simple and inexpensive attachment for oil well casings, which will effectively extinguish the flame, in case the outrushing gas and oil should catch fire, provision being made whereby two flat 10 blankets or jets of live steam may be forcibly projected across the passage through which the well is shooting, it having been proven by experience that this method of extinguishing is exceptionally efficient, as 15 oil wells throwing a stream of flame approximately two hundred feet in the air, have been successfully extinguished by the invention, with ease.

With the foregoing in view, the invention 20 resides in the novel subject matter herein-after described and claimed, the description being supplemented by the accompanying drawing.

Figure 1 is a vertical sectional view showing one form of my invention.

Figure 2 is a sectional view at right angles to Fig. 1, as indicated by line 2-2 thereof.

Figure 3 is a horizontal section on line 3-3 of Fig. 1.

Figure 4 is a longitudinal sectional view showing a slightly different form of construction.

Figure 5 is a side elevation.

In the drawings above briefly described, the numeral 1 designates a vertically elongated passage member which is preferably formed from a short length of piping, such as well casing, the lower end of said passage member being externally threaded as indicated at 2, whereby an appropriate coupling 3 may be provided for mounting said member upon the upper end of a well casing 4. The upper end of the body member 1 is 45 also preferably threaded as indicated at 5, so that a casing head, pipe section or the like, may be coupled thereto.

Between its ends, the passage member 1 is enlarged by welding, brazing or otherwise securing a hollow collar 6 around the same, said collar having steam inlet means which preferably consists of a pair of diametrically opposite ports 7 into which live steam supply pipes 8 may be threaded.

The passage member 1 is formed with a 55 pair of vertically spaced steam inlet ports 9, in the form of slits formed through the wall of said member between the interior of the latter and the interior of the hollow enlargement or collar 6. The upper port 9 60 extends substantially throughout half the circumference of the passage member 1 and is at the side of the device adjacent one of the steam inlets 7. Similarly, the other port 9 occupies approximately the other circumferential half of the passage member and is disposed adjacent the other steam inlet. The opposed walls of the slits or ports 9 may either be disposed in horizontal planes as indicated in Fig. 4, or they may be 70 slightly inclined as disclosed in Figs. 1 and 2. It will be seen that as soon as live steam is permitted to pass through the pipes 8, it will entirely fill the hollow collar 6, around the passage member 1 and the steam from this space will be forcibly directed across the passage member, in vertically spaced planes, by means of the ports 9, forming flat jets or blankets of steam which co-operate in effectively chocking down the discharge from the well and extinguishing the flame.

While in the present application, I have disclosed only one form of construction, it is to be understood that within the scope of the invention as claimed, numerous modifications may be made.

I claim:

1. An oil well fire extinguisher comprising a passage having a slot in its side for directing a flat blanket of steam across the passage, the side walls of said slot being disposed on lines oblique to the passage axis to direct the steam obliquely across said passage, and a steam inlet for supplying steam to said slot.

2. An oil well fire extinguisher comprising a passage and means associated with said passage for directing one flat blanket of steam obliquely upward across the passage 100 and for directing another flat blanket of steam obliquely downward across said passage.

3. A fire extinguisher comprising a vertically disposed passage member having a circumferentially extending chamber and upper and lower steam inlet slots opening from said chamber into the interior of the

2

passage, one of said slots extending substantially throughout half the circumference of the passage while the other slot extends substantially throughout the remainder of such 5 circumference, and means for supplying steam to said chamber.

4. A fire extinguisher comprising a body having means for connecting it to a well casing, said body being provided with a 10 passage for communication with the casing, with a chamber around the passage, and with slots from said chamber into said passage, said slots being disposed in a plurality of spaced transverse planes and occupying 15 different segmental portions of the circumference of the passage, and means for admitting a non-combustible fluid to said chamber for discharge into the passage through said slots.

20 5. A structure as specified in claim 7; said

slots jointly extending substantially through-out the circumference of the passage.

6. A fire extinguisher comprising a vertically elongated passage member having means at its lower end for coupling it to an 25 oil well casing, said passage member having a hollow enlargement which circumferentially surrounds said member and provides therewith an annular chamber, said chamber being provided with steam inlet means, said 30 passage member having an upper and a lower port leading from said chamber to the interior of said passage member, one of said ports occupying substantially half the circumference of said passage member while 35 the other port occupies substantially the remainder of such circumference.

In testimony whereof I have hereunto affixed my signature.

EDWARD ALBERT KLEWER.
